Application filed October 14, 1893. Serial No. 488,174. Term of patent 3½ years.

To all whom it may concern:

Be it known that I, CHARLES BOOZE, a citizen of the United States, residing at Buffalo, in the county of Erie and State of New York, 5 have invented and produced a new and original Design for Wall-Paper, of which the following is a specification.

The design consists of a series of ornamental scrolls of the style of Louis XV disposed at 10 regular distances apart and forming panel shaped figures, with flowers and leaves arranged in the center of said panels and springing from vase-like ornaments attached to said scrolls as represented in the accompanying 15 drawing. The border or upper portion of the

design is formed of similar ornamental scrolls forming panels with flowers and leaves in the center and festoons of flowers and leaves connecting said scrolls as shown.

What I claim is—

1. The design for wall paper shown and described.
2. In the design for wall paper the border herein shown and described.

Witness my hand this 5th day of October, 25 1893.

CHARLES BOOZE.
